UNITED STATES PATENT OFFICE.

WILLIAM M. GALLAGHER, OF CARNEGIE, PENNSYLVANIA.

TORPEDO.

SPECIFICATION forming part of Letters Patent No. 628,308, dated July 4, 1899.

Application filed May 14, 1898. Serial No. 680,717. (No model.)

To all whom it may concern:

Be it known that I, WILLIAM M. GALLAGHER, a citizen of the United States of America, residing at Carnegie, in the county of Allegheny and State of Pennsylvania, have invented certain new and useful Improvements in Harbor-Torpedoes, of which the following is a specification, reference being had therein to the accompanying drawings.

10 This invention relates to certain new and useful improvements in torpedoes, and it relates particularly to a torpedo to be used for submarine purposes.

The invention aims to provide a torpedo of this class in which simplicity of construction, absolute safety in handling, and the assured explosion of which, together with effectiveness, will be combined, as will be hereinafter more specifically described, and particularly 20 pointed out in the claim.

The invention further aims to provide a torpedo of this class which may be filled with its charge of explosives, electrical wires or other exploding means connected therewith, 25 and the torpedo safely deposited beneath the water without interfering in any manner with the means for exploding the charge at the desired time. Means is also provided for retaining the torpedo submerged and for suspending the same at the desired position in the water, as well as for the absolute sealing of the torpedo, so as to prevent any dampness accruing to the charge of explosives 30 therein.

35 In describing the invention in detail reference is had to the accompanying drawings, forming a part of this specification, and wherein like figures of reference indicate similar parts throughout the several views, in which—

40 Figure 1 is a side view of my improved submarine or harbor torpedo. Fig. 2 is a longitudinal sectional view of the same. Fig. 3 is a perspective view of one of the disks, which are filled with mercury, fulminate, or other explosive and are connected to the exploding-wire. Fig. 4 is a like view of a modified form 45 of this disk.

To put my invention into practice, I form of cast-steel or other suitable material a shell 50 1, which is or may be of an oval form, as herein shown in the drawings, or this shell may be of any desired shape and may of

course be of any size desired, according to the effectiveness which it is desired to attain from the torpedo. This shell is formed on its upper side with a dome 2, through which the charge of explosives 3 is placed within the shell, and on its interior wall at its lower side directly underneath the dome the same is formed with an upwardly-extending annular 55 flange 4, which is adapted to receive a tube 5, which is inserted through the dome and is held in position by means of the said annular flange 4. This tube 5 is provided for the purpose of receiving the mercury or other explosive disks and which permits the anchoring of the same at the base of the charge of explosives. When filling the shell with its charge, the top of the tube may be covered and the charge of explosives then poured 60 within the shell until the latter is filled, at which time the disks, percussion-caps, or other exploding device are inserted in the tube and anchored upon the inner wall of the shell at the base of the said tube. Two of these disks, 65 as shown at 6 in Fig. 3, may be employed, and the igniting-wire 7 may be formed with two branches 8, one of which is connected to each of the disks, or, if desired, the igniting-wire 7 may be attached to a circular disk or 70 percussion-cap 9, as is shown in Fig. 4. After the disks have been anchored in their position the tube 5 may be likewise filled with an explosive charge, and the torpedo is then sealed by means of a layer of paraffin 10, 75 which is placed within the dome on top of the explosives, and then closing the dome by means of the screw-cap 11, which is of course provided with a central aperture to receive the igniting-wire 7. Within the annular 80 flange of this cap 11, which engages the screw-thread of the dome 2, I may provide a gasket 12, of any suitable flexible material, which will bind firmly upon the igniting-wire and prevent any danger of water passing into the 85 shell through the aperture in the cap, which is provided for the igniting-wire. The paraffin 10 will also solidify closely around said wire and prevent any dampness reaching the charge of explosives if by any chance whatever it might pass the cap and gasket. 90

For the purpose of retaining the torpedo submerged, for suspending the same at the desired distance, and for lowering the same

into the water I provide bands 14, which preferably conform to the exterior wall of the shell 1 and are swaged or otherwise firmly secured thereon. These bands carry eyelets 15 at the top of the shell, eyelets 16 at the lower portion of the shell, and eyelets 17 at the sides thereof. The eyelets 15 are adapted to receive the cables which suspend the torpedo at the desired position and may also be employed for connecting a series of the torpedoes together. The eyelets 16 are provided for the purpose of lowering the torpedoes to their anchorage without interfering in any manner with the cables which are or may be attached to the eyelets 15 and 17. I may also provide the shell 1 with an eyelet 18 on its lowermost side, as shown in the drawings, which may be used for various purposes, or I may provide the shell with a number of these eyelets, as may be desired.

By branching the igniting-wire within the tube 5 an absolute certainty of explosion is assured, as in case one of the percussion-caps or mercury-disks refuses to be exploded the other would act, and thereby assure the exploding of the main charge. This, however, is very unlikely, owing to the perfect manner in which the torpedo is sealed, and the form of exploding-disk or percussion-cap as shown in Fig. 4 may be employed.

It will be observed that in such a construction the torpedo may be charged with explosives and after the connections have been

made the same may be hermetically sealed and safely lowered to its position beneath the water without danger of a premature explosion.

Having fully described my invention, what I claim as new, and desire to secure by Letters Patent, is—

A harbor-torpedo comprising a substantially oblong-shaped cast shell having an open dome formed integral therewith through which the explosive charge may be inserted into the shell, a central annular flange formed integral with the inner face of the shell at a point directly in line with the open dome, a central tube secured in said annular flange and an explosive charge therein, an electric fuse connected with the explosive charge within the central tube, a screw-cap engaging said open dome and provided with a central aperture to receive the fuse, a filling of paraffin or other air-excluding substance on top of the explosive charge within the open dome, a gasket interposed between said filling and the screw-cap, and a pair of bands swaged to the exterior of the cast shell and provided with eyelets, substantially as herein described.

In testimony whereof I affix my signature in the presence of two witnesses.

WILLIAM M. GALLAGHER.
